To all whom it may concern:

Be it known that I, CHARLES F. The figure is a plan view of a portion of linoleum or similar hard-surfaced floor covering, showing my design, it being understood that the design in the representative illustration is repeated throughout the ex-

tent of the linoleum or similar hard-surfaced floor covering.

The design is preferably executed in various shades or colors, although the particular shadings employed in the illustration are not intended to indicate any particular colors.

I claim:

In testimony whereof I have hereunto set my hand.
